UNITED STATES PATENT OFFICE

RALPH E. BATES, OF WEST MEDFORD, MASSACHUSETTS, ASSIGNOR TO WILLIAMS, WHITE & COMPANY, OF MOLINE, ILLINOIS, A CORPORATION

PNEUMATIC POWER HAMMER

Application filed July 30, 1926. Serial No. 126,033.

This invention relates to pneumatic power hammers.

In the particular type of hammer to which my invention is applied, the principal elements of the hammer are all incorporated in a main frame.

In the upper section of the frame is a hammer cylinder in which reciprocates a piston rigidly secured to a ram by means of which 10 the hammer mounted on the lower end of the ram is given its motion toward and from the anvil. The anvil is set in a foundation directly beneath the hammer. In the lower section of the frame is a power cylinder containing a piston which is reciprocated within a cylinder by a motion received from a crank and connecting rod.

Power may be delivered to the crank in any convenient way. I have chosen to show here- 20 with tight and loose pulleys adapted to be rotated from a belt connected to a source of power.

Both cylinders are double acting, that is to say, both the up and down strokes of the 25 pistons are employed to do effective work in the operation of the hammer. The two cylinders are connected by a system of conduits cooperating with a manually operated valve whereby any of three distinct operating 30 conditions, to be described later, may be attained and also conditions intermediate of the three major conditions may be brought about by a manipulation of the valve.

The medium used to transmit power from 35 the power driven piston to the hammer cylinder is air under pressure. Supplementing the action of the air pressure is the suction due to the presence of a partial vacuum within the cylinders at certain periods in the cycle 40 of operation of the machine.

The principal object of my invention is to provide a pneumatic hammer of the above-described type which is composed of a minimum number of parts and is of a highly efficient design, thus producing a machine which 45 will be economical to manufacture and to maintain in operation.

An additional object of my invention is to produce a pneumatic hammer which will be 50 compact in form and rigid by incorporating

the power cylinder into the base section of the machine.

A further object of the invention is to provide a pneumatic hammer that will be flexible in operation and that may be readily and quickly changed from one to another of the following operating conditions, first, that condition where the device is delivering its full capacity of hammer blows, which blows may be varied from a maximum to a very light blow, second, where the hammer is lifted and held in its uppermost position and, third, where the hammer is held down against the work, thus vising or clamping it between the hammer and anvil.

Another object of the invention is to provide a double-acting power cylinder to be used in the above described power hammer in which both the up and down strokes are used to do effective work in the operation of the machine with a consequent gain in operating efficiency.

A further object of the invention is to provide a construction in which the frame of the machine is in two main sections, the top section containing the hammer cylinder and having formed integral therewith certain of the communicating conduits between the power and hammer cylinders and also forming a closure for the power cylinder, the lower section containing the power cylinder and having formed therein a conduit communicating with the lower end of the power cylinder, the lower section also forming a closure for the hammer cylinder.

Other objects and features of the invention will more fully appear from the following description and accompanying drawings and will be pointed out in the claims.

In the drawings:

Fig. 1 is a side elevation of a pneumatic hammer embodying my invention.

Fig. 19 is a section taken on line 19—19 of Fig. 4.

Fig. 20 is a sectional view on line 20—20 of Fig. 1.

The main frame of the machine consists of upper and lower sections 1 and 2 which are bolted or clamped together in any suitable way at 3. In the upper section is formed the hammer cylinder 4 within which reciprocates a piston 5 rigid with a ram 6. A continuation 7 of the ram extends into and has a close running fit in a supplementary cylinder 8. The continuation 7 of the ram has two flat faces 9 which prevent the ram from rotating. The ram 6 has an accurate bushed bearing 10 formed in an extension of the lower section 2 of the frame. This bearing, which is extra long, forms a substantial seal against leakage of air from the hammer cylinder.

Due to the fact that the continuation 7 of the ram fits the supplementary cylinder 8 closely, a certain amount of air is trapped within the supplementary cylinder and put under compression by the upward motion of the ram 6. Substantially half way up in the supplementary cylinder 8 is an air conduit 9 open to the atmosphere through which air escapes during the upward movement of the continuation 7 of the ram until the latter reaches the conduit 9, which is then closed

by the continuation 7 and further upward movement of the latter compresses the remaining air in the supplementary cylinder.

A head 10 is bolted upon the upper end of the supplementary cylinder 8 in which is mounted a check valve 11. A seat 12 is formed in the lower face of the head 10 against which the valve 11 is held by a compression spring 13 surrounding the valve stem and seated at one end on a collar 14 on the end of the valve stem and at the other end upon a perforated supporting web 15 integral with the head 10. A collar 14 is formed with an overhanging skirt which covers the perforations in the supporting web 15 excluding dirt therefrom.

One function of the check valve 11 and supplementary cylinder 8 is to cushion the upward movement of the ram 6. The valve 11 traps the air under compression and holds the pressure until upon the downward movement of the continuation 7 of the ram a pressure below atmospheric may be created in the cylinder 8 at which time the valve 11 will open and thus prevent any drag upon the ram due to a vacuum in the cylinder 8. The trapped air in the cylinder 8 will cause the ram to come to rest gradually and by the re-expansion of the air the ram will be started on its downward movement.

The power cylinder 16 is formed integral with the base section 2 and has a reciprocating piston 17 fitted therein which is provided with piston rings 18. The piston 17 has a lower portion 17a of smaller diameter which performs the function of a piston rod and has a close running fit in the head of the cylinder which provides a sufficient seal against escaping air. The piston 17 is reciprocated by a crank 19 and connecting rod 20. One end of the connecting rod 20 has a bearing on a crank pin 21 upon the crank 19 and at the other end it has a bearing upon a wrist pin 22 mounted on the piston 17. The crank 19 is mounted upon a shaft 23 journalled at one end in the base section 2 and at the other end in a bearing block 24 fixed to an integral platform member 25. The shaft 23 may be rotated by any suitable means and I have herein shown a fast and loose pulley 26 and 27 mounted thereon and adapted to receive power from any suitable source.

Upon the end of the ram 6 is mounted the hammer head 28 to which may be secured the die 29. Directly beneath the hammer head is the anvil 30 upon which is mounted a complementary die member 31.

A controlling valve 32 is mounted for rotation within a valve sleeve 33, which in turn is mounted in an aperture 34 extending all the way through the upper section 1 of the frame. This sleeve is held against rotation by a key 35. A short shaft 36 is fixed in the end of the valve and extends through, and has a bearing in, a plate 37 bolted to the frame section 1 and extending a short distance with-

in the aperture 34. The handle 38 is secured to the shaft 36 by which the valve is manually rotated. Longitudinal movement of the valve within the sleeve is prevented by a retaining plug 39 fitted tightly into the aperture 34 and bearing against the end of the valve 32. The rotation of the valve is limited by a pin 40 in the valve 32 which moves in a cut-away portion 41 of the valve sleeve 33. This cut-away portion is of the proper dimension and location to stop rotation of the valve at the limit of its motion in either direction.

The action of the hammer is controlled by various conduits in the valve which cooperate with conduits in the sleeve and communicating conduits in the upper and lower end of the power and hammer cylinders, the details of which will be described later. A further element which cooperates with the controlling valve 32 is a check valve 42 which is mounted in a frame 43, which in turn is inserted in a chamber 44 and held therein by bolting a flange integral therewith to the upper section of the frame 1. The check valve 42 is held upon its seat 45 by a compression spring 46 seated at one end against an adjustable collar 47 upon the valve stem and at the other end against a wall 48 integral with the frame 43. Extending from the wall 48 is a long boss 49 through which the valve stem extends and is guided and which, together with the wall 48, prevents air from escaping from the chamber 50. The chamber 50 is isolated from the chamber 44 by the valve 42.

The purpose of the valve sleeve 33 is merely to provide a means of readily restoring a good fit after the valve and sleeve have become worn. It will be noted that the conduits in the sleeve 33 register with the various conduits leading to the different parts of the machine. Consequently the conduits in the sleeve and the conduits registering therewith will be considered as one and referred to by a single character.

The controlling valve 32 has a relatively large conduit 51 out of which leads another conduit 52. A conduit 53 of the same longitudinal dimension as the conduit 51 leads to the lower end of the power cylinder 16 and is always in communication with the conduit 51. Another conduit 54 leads to the lower end of the hammer cylinder 4 and by rotation of the controlling valve may be brought into relation with various other conduits, as will hereinafter more fully appear. Another conduit 55 communicates with the chamber 50 and may be made to register with the conduit 52 only. A conduit 56 in the valve 32 registers with a conduit 57 leading into the chamber 44. While the valve 32 is in the elevating position, which will hereinafter be described, the conduit 57 will communicate with the conduit 54 through the conduit 56 in the valve 32. At

all other positions of the valve 32 the conduits 56 and 57 have no function.

Leading out of the top of the power cylinder 16 is a conduit which communicates at all times with the conduit 59 in the valve 32. Another conduit 60 leads to the top of the hammer cylinder 4 and communicates with the conduit 58 at certain positions of the controlling valve 32 which will be explained later. A conduit 61 in the valve 32 serves as a by-pass from the chamber 44 into the conduit 58 and thence to the upper end of the hammer cylinder, while the valve is in the position that will later be described as a vising position.

An exhaust conduit 62 leads into a chamber 63 which has an outlet to the atmosphere 64. The chamber 63 is made sufficiently large to constitute an effective muffler which will thus quiet the noise of the exhausted air. This exhaust conduit communicates with the conduit 59 in the valve 32 at certain times and is closed at other times. A conduit 66 serves as a by-pass between the conduit 54 leading to the bottom of the hammer cylinder and the conduit 59 in the valve when the valve is in the vising position.

The control valve 32 may be operated by the handle 38 or by a lever 67 pivoted at 68 which acts to operate the handle 38 through a removable connecting member 69 between the handle 38 and one end of the lever 67. A further means of operating the control valve is provided by a foot-actuated lever 70 pivoted at 71 and having a connecting link 72 interposed between the lever 70 and the lever 67 by means of which the motion of the lever 70 is transmitted to the lever 67 and thus through the connecting member 69 to the handle 38. By disengaging the member 69 from the handle 38, the device may be operated from the latter independently of the levers 70 and 67. The extreme upward position of lever 70 causes the hammer to be raised and held away from the work while the extreme downward position of the lever is the position of full blow. It is necessary therefore to disconnect the connecting member 69 in order to throw the valve into vising position. Such an arrangement prevents the operator from unintentionally using the vising position and thus simplifies the operation of the hammer since the other and more important functions can be entirely controlled by a comparatively slight motion of the controls without attempting to avoid the vising position.

There are three major positions of the control valve 32 which result in certain operating conditions of the hammer. All intermediate positions cause a gradual change from one condition to another. The three major operating conditions will be called full blow, elevating and vising.

At the full blow condition the hammer is

striking its full length of stroke and with its maximum force. The piston 17 is reciprocated continuously by the crank 19 and the connecting rod 20. Referring particularly to Figs. 2, 5, 6, 7 and 8, which show the valve in full blow position, it will be apparent upon the downstroke of the piston 17 that air under pressure will be forced through the conduit 53, the valve conduit 51 and thence into the lower end of the hammer cylinder through conduit 54, thus raising the piston 5. As the piston 17 descends, a partial vacuum is created in the top of the cylinder 16. It will be noted that at this time the conduit 58 leading to the top of the cylinder 16 is in communication with the conduit 60 leading to the top of the hammer cylinder through the valve conduit 59. Thus a reduction of pressure is brought about above the piston 5, thus raising the hammer 28.

Upon the upstroke of the piston 17, a reversal of the above operations takes place. Air under pressure from the top of the cylinder 16 is forced into the top of the hammer cylinder 4, forcing the piston 5 down, which action is supplemented by a reduction of pressure under the piston 5 due to the vacuum created in the lower end of the cylinder 16 by the upstroke of the piston 17. At the top of the upstroke of the piston 17, the air pressure is immediately relieved and drops to atmospheric level by escaping through conduits 73 located near the top of the piston 17 as they register with conduits 74 formed in the top of the cylinder 16. The escaping air passes out through the interior of the piston 17 which is open to the atmosphere. Similarly atmospheric pressure is restored in the lower end of the cylinder 16 when perforations 75 in the lower section of the piston 17a are uncovered at the top of the upstroke of the piston 17.

This restoring of atmospheric pressure at the end of both the up and down strokes of the piston 17 has the effect of making the hammer work faster and more efficiently. The elasticity of the air, if the air were wholly confined, would make the action of the hammer sluggish. If the high pressure at the end of the upstroke were not reduced, it would merely expand upon the downstroke and have little or no effect upon the piston in the hammer cylinder. Likewise if the vacuum in the lower end of the cylinder 16 were not restored to atmospheric pressure, hardly any effective work would be done upon upon the next succeeding stroke of the piston 17.

We will next proceed to describe the condition where the hammer is elevated and held in its elevated position.

Figs. 11, 12, 13 and 14 show the control valve 32 in the proper position to elevate the ram.

Upon the downstroke of the piston 17 the air under pressure passes through conduit 53 into conduits 51 and 52 of the valve and thence into the chamber 50 through the conduit 55. This air under pressure forces its way past the check valve 42 into the chamber 44 and from there into the conduit 57 through the conduit 56 in the valve and out through the conduit 54 to the lower end of the hammer cylinder which raises the hammer. It will be noted that with the valve in the present position, both the conduit 60 from the top of the hammer cylinder and the conduit 58 from the top of the power cylinder are in communication with the exhaust conduit 62 through the conduit 59 in the valve. The result of the above described relative positions of conduits causes the upper end of the power cylinder to have no effect on the hammer as the air simply blows in and out of the exhaust conduit 62. The fact that the conduit 60 is open to the atmosphere allows the hammer to be raised freely.

When the power piston 17 rises, a vacuum will be created in the conduit 53, but this vacuum will have no effect upon the piston 5 as the check valve 42 prevents any negative pressure from passing into the lower end of the hammer cylinder 4, thereby nullifying the upstroke of the power piston 17 and making effective the pressure or downstrokes of the piston 17, the result of this being that the hammer will rise and remain in its elevated position. On the upstrokes of the power piston 17, the air merely expands idly, producing no effect.

It may be judged from the previous explanation of the action of the continuation of the ram 7 and the supplementary cylinder 8 that the piston 5 can never reach the top of the hammer cylinder. However, there is a gradual leakage of air that takes place in the cylinder 8 through the valve 11 and between the continuation of the ram 7 and the walls of the cylinder 8, thereby permitting the piston 5 to gradually rise to the top of the cylinder.

The next condition is the vising condition wherein the hammer is lowered and held down on the work, vising or clamping it against the anvil.

Figs. 15, 16, 17, 18 and 19 illustrate the valve in the vising position. As the power piston 17 descends, air under pressure passes into the conduit 53 through the conduits 51 and 52 of the valve into the conduit 55 communicating with the chamber 50. It now passes through the check valve 42 and into the chamber 44 and thence out of the only available conduit 65. It then passes into the conduit 60 leading to the upper end of the hammer cylinder through the by-pass conduits 61 in the valve 32. The result of this is to force the piston 5 downwardly. The vacuum created by the upstroke of the piston 17

17 is checked by the check valve 42 in the same manner as above described in the elevating condition. The result of the foregoing is that the down strokes of the power piston 17 are used to force the hammer down upon the anvil while the upstrokes of the power piston are nullified by the action of the check valve, which results in holding the hammer down against the work.

10 As shown in Fig. 18, the conduit 58 is in communication with the exhaust conduit 62 through the conduit 59, thus allowing the air in the top of the power cylinder 16 to pass freely in and out of the exhaust conduit 62.

15 In Fig. 17 it will be noted that the conduit 66 communicates with the conduit 54 leading to the lower end of the hammer cylinder. The conduit 66 also communicates with the conduit 59 in the valve 32 which is open to the exhaust conduit 62 and the atmosphere. Thus the air beneath the piston 5 is vented to allow it to descend.

20 As has been indicated previously, the hammer may be held in any position throughout its stroke and may be made to deliver a blow of varying power by setting the controlling valve 32 at various points intermediate of the three major positions.

Having thus described the invention, what 25 is claimed as new, and desired to be secured by Letters Patent, is:

1. In a pneumatic hammer, the combination with a power cylinder having a driven piston therein, a hammer cylinder, a piston reciprocable therein, a ram rigid with the latter piston, a hammer upon the end of the ram, a valve seat, conduits connecting said seat with the ends of the cylinders and the atmosphere and a valve movable on said seat 30 to control the passage of air in said conduits, of an enclosed supplementary cylinder mounted upon the end of the hammer cylinder, an elongation of the ram reciprocable within the supplementary cylinder and acting as a piston therein, an inwardly-opening check valve within the supplementary cylinder communicating from the chamber above the ram to the atmosphere and maintaining the pressure in said chamber at or above atmospheric pressure so that upon the upstroke of the hammer air is compressed within said chamber causing the hammer to come to rest gradually and by the re-expansion of the air reversing the motion of the hammer.

35 2. In a pneumatic hammer, the combination with a power cylinder having a driven piston therein, a hammer cylinder, a piston reciprocable therein, a ram rigid with the latter piston, a hammer upon the end of the ram, conduits communicating between the cylinders, and means to control the passage of air in said conduits, of an enclosed supplementary cylinder mounted upon the end of the hammer cylinder, an elongation of the 40 ram reciprocable within the supplementary

cylinder and acting as a piston therein so that upon the upstroke of the hammer air is compressed within said chamber causing the hammer to come to rest gradually and by the re-expansion of the air reversing the motion of the hammer.

3. In a pneumatic hammer, the combination with a power cylinder having a driven piston therein, a hammer cylinder, a piston reciprocable therein, a ram rigid with the latter piston, a hammer upon the end of the ram, conduits communicating between the cylinders, and means to control the passage of air in said conduits, of an enclosed supplementary cylinder mounted upon the end of the hammer cylinder, an elongation of the ram reciprocable within the supplementary cylinder and acting as a piston therein, an inwardly opening check valve within the supplementary cylinder communicating from the chamber above the ram to the atmosphere and maintaining the pressure in said chamber at or above atmospheric pressure so that upon the upstroke of the hammer air is compressed within said chamber causing the hammer to come to rest gradually and by the re-expansion of the air reversing the motion of the hammer.

4. In a pneumatic hammer, the combination with a power cylinder having a driven piston therein, a hammer cylinder, a piston reciprocable therein, a ram rigid with the latter piston, a hammer upon the end of the ram, conduits communicating between the cylinders, and means to control the flow of air in said conduits, of an enclosed supplementary cylinder mounted upon the end of the hammer cylinder, an elongation of the ram reciprocable within the supplementary cylinder and acting as a piston therein, and means to maintain the pressure in the chamber above the ram at or above atmospheric pressure so that upon the upstroke of the hammer air is compressed within said chamber causing the hammer to come to rest gradually and by the re-expansion of the air reversing the motion of the hammer.

In testimony whereof, I have signed my name to this specification.
